UNITED STATES PATENT OFFICE.

THOMAS A. MITCHELL, OF READING, MASSACHUSETTS, ASSIGNOR TO MERRIMAC CHEMICAL COMPANY, OF NORTH WOBURN, MASSACHUSETTS, A CORPORATION OF MASSACHUSETTS.

METHOD OF MAKING METALLIC ARSENATES.

1,183,315.

Specification of Letters Patent. Patented May 16, 1916.

No Drawing.

Application filed July 23, 1915. Serial No. 41,497.

To all whom it may concern:

Be it known that I, THOMAS A. MITCHELL, a citizen of the United States, residing at Reading, in the county of Middlesex and 5 State of Massachusetts, have invented certain new and useful Improvements in Methods of Making Metallic Arsenates, of which the following is a specification.

This invention relates to a novel method 10 whereby arsenates of lead, or other metallic arsenates, may be prepared directly and in a single operation from the corresponding metals.

The present commercial processes of making arsenate of lead utilize litharge as a 15 source of lead, in conjunction with either sodium arsenate or arsenic acid. Inasmuch as the litharge must be prepared from metallic lead by a preliminary operation, it is 20 obvious that a method which yields the arsenate directly from metallic lead, and without any expenditure of power for the electrolysis of solutions, represents a material industrial advance.

According to the present invention, arsenate of lead may be prepared directly from 25 metallic lead, white arsenic (arsenic tri-oxid) and nitric acid. An example of a preferred procedure is as follows:—25 kilos 30 of white arsenic and 60 kilos of metallic lead are placed in a covered stoneware vessel, from which a pipe leads to an absorber for recovering the oxids of nitrogen evolved during the process. To this charge is added 35 slowly, preferably with stirring, 25 kilos of commercial nitric acid of 40° Baumé. The temperature tends to rise as the reaction proceeds, but it is not permitted to go above 90° C., being controlled either by limiting 40 the rate of inflow of the acid or by suitably cooling the contents of the vessel. As soon 45 as the acid has all been admitted and the temperature within the vessel begins to fall, steam is introduced to maintain the temperature and complete the reaction. At the 50 close of the operation the liquid contents of the vessel are drawn off, and the lead arsenate is collected on filters and washed. In the course of this process, nitric acid reacts with arsenic trioxid, forming arsenic acid, and being itself reduced to oxids of nitrogen. These gaseous oxids are reoxidized in the absorbing system in contact with water and in presence of an excess of air or oxy-

gen; and inasmuch as this reoxidation is 55 practically quantitative, there is an almost complete recovery of nitric acid in condition for re-use in a succeeding operation. Simultaneously, the metallic lead is acted upon with the formation of small quantities 60 of lead nitrate, which are at once precipitated as the arsenate or arsenite of lead, or both, any lead arsenite which may be formed undergoing further oxidation to arsenate in presence of the nitric acid. In this manner, 65 there results at the close of the reaction a commercially pure arsenate of lead. It has been found advisable to introduce the nitric acid slowly, as above described, in order to maintain practical control of the reaction at 70 all times and to secure a complete absorption and recovery of the oxids of nitrogen. It has been found that when the reaction is properly conducted there is substantially no formation of N_2O , the production of which 75 would involve a corresponding loss of nitrogen.

The spent liquors from the process contain small quantities of nitric acid and lead nitrate, and are essentially similar in composition to the spent liquors obtained in the direct preparation of lead arsenate from metallic lead and arsenic acid, as described in my copending application Serial No. 41,498, filed July 23, 1915, and they may if 85 desired be employed in conjunction with the said process.

The present method is highly advantageous in practice, inasmuch as it utilizes metallic lead without necessity for first converting it into litharge; and also utilizes arsenic trioxid, the oxidation of which takes place in the same container and at the same time as the formation of the arsenate of lead. 95

It will be understood that the reagents may be proportioned to yield the tri-, di-, or mono-basic arsenate of lead, as may be desired. Also, if desired, the method may be applied directly to the production of metallic arsenates other than those of lead, as for example arsenate of copper, zinc, iron or tin, by substituting the corresponding metal for the metallic lead. 100

I claim:—

1. The method of making metallic arsenates, which consists in subjecting arsenic trioxid to oxidation in presence of the metal 105

entering into the constitution of the arsenate.

2. The method of making an arsenate of lead, which consists in subjecting arsenic trioxid to oxidation in presence of metallic lead.

3. The method of making an arsenate of lead, which consists in subjecting arsenic

trioxid to oxidation by the agency of nitric acid in presence of metallic lead.

In testimony whereof I affix my signature in presence of two witnesses.

THOMAS A. MITCHELL.
